US0D1003873S

(12) **United States Design Patent** (10) **Patent No.:** **US D1,003,873 S**
(45) **Date of Patent:** **** Nov. 7, 2023**

(54) **MICROPHONE**

(71) Applicant: **Harman International Industries, Incorporated**, Northridge, CA (US)

(72) Inventors: **Yanyang Jia**, Shenzhen (CN); **Alexander Demin**, Shenzhen (CN); **Tao Lu**, Shenzhen (CN); **Hoyean Kim**, Shenzhen (CN); **Chris Hansen**, Northridge, CA (US); **Karam Kaul**, Studio City, CA (US)

(73) Assignee: **Harman International Industries, Incorporated**, Northridge, CA (US)

(**) Term: **15 Years**

(21) Appl. No.: **29/805,952**

(22) Filed: **Aug. 31, 2021**

(51) LOC (14) Cl. **14-01**

(52) U.S. Cl.

USPC **D14/228**

(57) **CLAIM**

The ornamental design for a microphone, as shown and described.

DESCRIPTION

FIG. 1 is a front perspective view of a microphone showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines adjacent the shaded areas represent the bounds of the claimed design, while all other broken lines are directed to environment; the broken lines form no part of the claimed design.

1 Claim, 7 Drawing Sheets
